UNITED STATES PATENT OFFICE

LOUIS GARBARINO, OF DETROIT, MICHIGAN, ASSIGNOR TO A. HARVEY'S SONS MFG. CO.,
A CORPORATION OF MICHIGAN

JOINER GUARD

Application filed November 3, 1930, Serial No. 492,975. Renewed September 21, 1931.

This invention relates to a guard for covering the cutter of a joiner or the like.

The main objects of this invention are to provide an improved guard, which, by both 5 horizontal and vertical movement with respect to the cutter, will be readily moved away from the cutter by insertion of the stock fed to the cutter and which will automatically return to its original covering and 10 guarding position immediately upon the removal of the stock being worked; to provide an improved guard which may be rotated on its mounting bracket to a position entirely free and clear of the joiner table if desired; to provide an improved guard which 15 normally rests upon the joiner table in tilted position so that only one edge contacts with the table and the major portion thereof is held in spaced relation above the cutter, and 20 to provide a simple unitary assembly of guard and mounting which may be quickly and easily attached to existing types of joiners and the like now in use.

An illustrative embodiment of this invention is shown in the accompanying drawings, in which

Fig. 1 is a view in perspective of a joiner equipped with my improved guard and showing a piece of stock inserted between the 30 guard and the vertical guide of the table.

Fig. 2 is a similar view showing a piece of stock material inserted underneath the guard.

Fig. 3 is a similar view showing the guard 35 rotated to a position entirely free and clear of the joiner table.

Fig. 4 is an enlarged sectional detail view taken on the line 4—4 of Fig. 5, looking in the direction indicated.

Fig. 5 is a top plan view of my improved guard and bracket mounting therefor.

Fig. 6 is an enlarged sectional detail view taken on the line 6—6 of Fig. 5.

Fig. 7 is an enlarged sectional detail view 45 taken on the line 7—7 of Fig. 5.

Fig. 8 is a view in perspective of the guard head with a portion of the supporting arm which supports the same.

In the construction shown in the drawings, a joiner 10 having a substantially rec-

tangular-shaped, horizontally disposed, elongated table 11 is provided with a cutter 12 protruding from the surface thereof and disposed transversely with respect thereto, which is journaled in bearings 13 and 14 in 55 the usual manner. An upstanding guide or back-board 15 is provided on the table 11 in the usual manner against which pieces of stock may be placed for guiding them over the cutter.

My improved guard is shown equipped on this joiner, and the guard per se comprises a mounting 16 provided with openings 17 and 18 through which bolts, cap screws, or other suitable securing means 19 and 20 may be 65 passed for securing the bracket to the front side edge 21 of the table 11 in spaced relation to the cutter 12 and at the far end of the table with respect to the direction of feed.

The bracket 16 is provided with a depending portion 22 which is provided with an outstanding shank 23 integrally formed thereon. The shank 23 is provided with a cylindrical bearing portion 24 of reduced diameter and the outer end of which is threaded at 25 for 70 the reception of a nut 26.

An intermediate member 27 is rotatably journaled on the bearing portion 24 and is retained thereon by the nut 26 which preferably has a washer 28 interposed between a 80 nut and the intermediate member. The intermediate member 27 is provided with a relatively short, integrally formed, rigid projection 29 which is disposed at an angle of substantially 45° with respect to the axis of 85 the journaled mounting between the intermediate member and the bearing portion 24 of the base member.

A side of the intermediate member is finished as a bearing surface for receiving a 90 substantially flat circular head 30 which is pivoted thereto by a cap screw 31, the shank of which is journaled through a lateral extension of the intermediate member 27, and a threaded portion 32 of which is threaded into 95 an upstanding boss 33 formed on the top side of the head 30. The head 30 is provided with a radially extending lug 34 which abuts against an upstanding lug or boss 35 integrally formed on the rigid projection 29 for lim- 100

ituting pivotal movement of the head 30 relative to the intermediate member 27. The head 30 is also provided with radially extending channel shaped arm 36 which is adapted 5 to receive one end of an elongated arm 37 in a channel thereof and be secured therein by screws 38 and 39.

The underside of the arm 36 adjacent the outer end thereof is provided with a depending lug 40 having a short stud 41 mounted therein in the path of travel of a similar stud 42 mounted in the rigid projection 29 of the intermediate member 27.

A helical compression spring 43 is interposed between the lug 40 and projection 29 with the opposite ends thereof surrounding and embracing the studs 41 and 42 which hold the spring in position for normally urging the arm 36 in one direction of its pivotal 20 movement.

The opposite end of the elongated arm 37 is rigidly secured to one end of a guard head 44 by screws 45 and 46. The guard head 44 is preferably made of aluminum or similar 25 light weight material and the front edge thereof is provided with a curved upwardly extending flange 47 which is adapted to cam the guard head upwardly when a piece of stock is pushed against the end thereof. The 30 inner end of the guard head is also curved rearwardly, as shown at 48, so that when a piece of stock 49, as shown in Fig. 1, is pushed thereagainst, the head will be cammed outwardly in a horizontal direction or to the 35 left as viewed in Fig. 1 of the drawings.

In the operation of the guard, it is attached to a joiner or the like with the upper edge of the bracket 16 slightly below the top plane of the table and in spaced relation to the cutter 40

12. In ordinary use, the guard head 44 rests upon the table top 11 in a tilted position so that the edge only of the guard is supported on the table and the major portion thereof covers over the cutter 12 in spaced relation 45 thereto.

When it is desired to trim the edge of a piece of stock, such as the piece 49 shown in Fig. 1 of the drawings, the stock is pushed against the upright support 15 and against 50 the rearwardly curved edge 48 of the guard 44, which cams the guard outwardly to the left against the action of the compression spring 43. As soon as the piece of stock 49 is removed from the joiner, the spring 43 will 55 automatically return the head 44 of the guard to its normal original position which is in contact or substantially in contact with the upright guide 15.

When it is desired to trim the side of a flat 60 piece of stock, the stock is pushed against the upwardly curved front edge 47 of the guide head, causing the guide head to be cammed upwardly and the piece of stock passes underneath, as shown in Fig. 2 of the 65 drawings. As soon as the piece of stock passes

over the cutter and beyond the guard head 44, the guard will return to its position of rest upon the table by gravity.

If it is desired to use the joiner for a large piece of stock material, which would interfere with the guard, the arm 37 of the guard is rotated about the axis of the bearing 24 upwardly, rearwardly and thence downwardly to the position shown in Fig. 3 of the drawings, wherein it is entirely free and clear of the joiner table 11 and due to its mounting at the lower end of the depending portion 23 of the bracket 16 all parts of the guide are out of the way of the stock being worked upon the joiner table.

The entire guard assembly may be attached as a unit to any existing type of joiner or the like quickly and readily by means of the cap screws or bolts 19 and 20.

Although but one specific embodiment of this invention has been herein shown and described, it will be understood that numerous details of the construction shown may be altered or omitted without departing from the spirit of this invention as defined by the following claim.

I claim:

A joiner guard comprising a base member, adapted to be mounted on a joiner, an intermediate member journaled on said base member, a rigid projection on said intermediate member, an arm having one end pivoted on said intermediate member on an axis substantially perpendicular to said journal axis, a compression spring interposed between said rigid projection and said arm for normally urging said arm in one direction of its pivotal movement, and a guard head on the other end of said arm.

LOUIS GARBARINO.
